No. 11,808

JUNE 8, 1880

UNITED STATES PATENT OFFICE.

RODOLPHE CHRISTESEN, OF NEW BRITAIN, CONN., ASSIGNOR TO THE RUSSELL & ERWIN MANUFACTURING COMPANY, OF SAME PLACE.

DESIGN FOR CHANDELIER-HOOK.

SPECIFICATION forming part of Design No. 11,808, dated June 8, 1880.

Application filed May 8, 1880. Term of patent 7 years.

To all whom it may concern:

Be it known that I, RODOLPHE CHRISTESEN, of the city of New Britain, and county of Hartford, and State of Connecticut, have invented a new and useful Design for Chandelier-Hooks; and I do hereby declare that the following specification, taken in connection with the accompanying illustration, forming a part of the same, is a full, clear, and exact description thereof.

The design hereinafter described is adapted to that variety of screw-hooks known as "chandelier-hooks;" and it consists of the following features:

15 The head *a* of the screw portion *A* has an

extension-top and a tapering body, which terminates in a bulbous end. This portion *a* is clasped by a youthful mermaid, *B*, the lower portion of whose body is curved and forms the hook *b*. The exact shape of this portion *a* may 20 be varied, as may also the sex and apparent age of the fabled animal clasping it.

What I claim, and desire to secure by Letters Patent, is—

The design for chandelier-hooks, substantially as described and shown.

RODOLPHE CHRISTESEN.
